UNITED STATES PATENT OFFICE.

LOUIS SCHOEN, OF BRONX, NEW YORK.

COMBINED WASHTUB AND SINK UNIT.

Application filed December 9, 1927. Serial No. 238,826.

My invention relates to a combined wash-tub and movable sink arranged to secure economy of space in kitchens, laundry rooms and the like and more particularly to a combined washtub and laterally swingable sink, wherein each is adapted to be used independently of the other, and a single pair of faucets provided to supply water to the tub and to the sink, respectively.

10 One of the objects of my invention is to provide a vertically and laterally movable sink, adapted to fit into and form a closure for the tub, and, in this position, to be at a convenient height for using the sink, and 15 means for lifting the sink vertically out of and above the tub, and whereby the sink may be swung on a pivot laterally to expose the top of the tub.

Another object of the invention is to provide the sink with independent drainage means, said means including a telescoping sleeve pipe, whereby the sink may be raised vertically, the sleeve pipe serving as a pivot in the lateral movement of the sink, without 25 disengaging the drain for the sink.

Other objects of the invention are to incorporate a hamper for soiled clothes with the tub, and also to provide that a cover for the hamper, which is also a cover for the 30 sink operating means, and supports the sink in its laterally moved position.

Another object of the invention is to secure greater economy of space and a better disposition of equipment than heretofore, by 35 providing a single unit comprising a wash tub, a vertically and laterally movable sink fitting therein, a pivoted washboard arranged in said tub, and a clothes hamper.

With the above and other objects in view, 40 my invention consists in the parts, improvements and combinations more fully pointed out hereinafter.

Referring now to the drawings:

Figure 1, is a top plan view, illustrating 45 the sink in its laterally moved position, supported by the hamper.

Figure 2, is a front elevation, partly in section, showing the sink moved away from the tub, supported by the hamper, and the 50 means for lifting the sink.

Figure 3, is a side view showing the sink lifted out of the tub, about to be swung laterally away from the tub, and the washboard in place for use in the tub.

Figure 4, is a top plan view, showing the sink in place in the tub and the means for lifting the sink, the cover section of the hamper being shown in its open position in dotted lines.

Figure 5, is a front elevation, showing the sink fitting into the tub, the hamper arranged adjacent to the tub, showing also, in dotted lines, the means for lifting the sink and the independent drain for the sink.

Figure 6, is a side elevation, showing the sink fitting into the tub, and the means for lifting the sink.

Figure 7, is a detail sectional view showing the lifting means for the sink passing through the perforated cornerpiece of the sink and the telescoping sleeve drain for the sink; the section being taken on line 7-7 of Figure 4.

In the drawings, the tub 1, is shown provided with a drain 2. Behind and above the tub, mounted on the wall, is splashboard 3, through which project faucets 4. A vertically movable and laterally swinging sink 5, is provided. This sink is suitably tapered so that its body portion fits within the tub 50 and its front and side walls are flanged as at 6, to rest upon the front and side walls of the tub and to be supported thereby.

Means are provided for lifting the sink vertically out of and above the tub, so that 55 the sink may be swung laterally away from the tub.

As illustrated, see particularly Figures 3 and 6, a handle 7, having lever arm 8, is pivoted by means of pivot pin 10, to the 60 side of the tub 1. By a pin and slot connection 11, lever arm 8 is connected to a vertically extending elbow arm 12, see Figures 2 ad 7, which projects through a cut-out portion provided in the cover section of 65 the hamper, to be hereinafter described. Elbow arm 12, at its distal end carries a hook member 13, which passes through a 70 perforated cornerpiece 14, provided in the sink 5. Hook 13, is provided with shoulders or collars 15, above and below the cornerpiece to prevent vertical movement of the hook in the cornerpiece. Hook 13, acts to lift the sink out of the tub and also 75 serves as a pivot member about which the sink may be swung laterally. It will thus be seen that the downward movement of handle 7, will raise lever arm 8, elbow arm 80

12 and hook 13, so that the sink will be lifted vertically out of and above the tub. The sink may then be swung laterally, by hand, about the hook member 13, passing through the cornerpiece of the sink, placing the tub ready for use and allowing the same faucets 4, which supplied the sink with water to now supply the tub.

Means are provided for providing the sink 10 with an independent drain, the said means being arranged so that the sink may be raised vertically and swung laterally away from the tub, about the drain, without disengaging the drain for the sink.

15 In the form of the invention illustrated, the tub 1, is provided with a drain conduit 16, extending upward into the tub, at the rear thereof, and adjacent the side of the tub on which the sink lifting means are arranged, this drain either standing in the corner of the tub or passing within the thickness of the tub wall. A sleeve drain pipe 17, carried by the sink is arranged to telescope with said drain conduit 16. By this 20 means the sink may, by its lifting means, be lifted vertically out of and above the tub, the sleeve pipe sliding upward in relation to the drain conduit, and the sink to be swung laterally, the telescopic drain also 25 serving as a pivot, without disengaging the drain for the sink.

Means are provided, additional to and arranged alongside of the tub for supporting the sink horizontally after it has been swung 30 away from the tub.

35 In the form of the invention illustrated, I provide a hamper 18, comprising a bottom compartment and a vertical compartment, and a cover section 19, built with the tub, beneath and alongside of the tub. Cover section 19, is hinged at 20, so that it may be swung open to permit access to the lifting means. When closed, cover section 19 is secured to the vertical compartment of 40 hamper 18, by means of latch 21, and normally encloses the sink lifting means, and closes the top entrance to the hamper. Cover section 19, is also provided at 22, with a cutout portion through which the vertically extending elbow arm 12 of the lifting means projects and operates. When section 45 19 is opened, the lifting means may be operated and the sink raised, after which the section is closed and the sink is swung about laterally to rest on and be supported by the cover section or by the entire hamper. The hamper is of a width sufficient to firmly support the sink in its moved position. Sink 5, is provided with a latch 23, for engaging the 50 top of the hamper and locking the sink in its moved position. The bottom compartment of the hamper which extends beneath the tub forming an enclosure for the space beneath the tub, between the tub and the 55 floor, is provided with a door 24, hinged at

25, through which the clothes may be withdrawn as desired.

The fixed part of the hamper is formed by walls suitably secured to or united with the tub, these walls enclosing all the space 70 beneath the tub and extending at one side of the tub in continuation with the lines of the tub. The section 19, which is hinged to swing horizontally also preferably conforms to the shape of the side or end of the tub. 75 This section forms a cover or housing for the operating lever and for affording access thereto and also a cover for the vertical portion of the hamper which stands contiguous with the side of the tub. When this 80 section or cover is open, clothes can be dropped into the hamper and will fall to the bottom. On opening the door 24, the clothes thus introduced can be drawn over into the part of the hamper cabinet beneath 85 the tub, or clothes can be put in through this doorway. The vertical portion of the hamper, at the side of the tub, does not take up much room and even a very small kitchen or kitchenette will accommodate the combination unit.

90 In the form of the invention illustrated, tub 1, has its front wall recessed as at 26, and in the depression thus formed, is pivoted a washboard 27, which may be formed of a sheet of metal corrugated in its body and provided with side flanges. Washboard 27, see Figure 3, is mounted below the top of the tub and is provided with legs 28, pivoted at 29, to the side flanges 30 of the board. 95 When the tub is in use, the washboard is swung out on its pivot, away from the front wall of the tub, so that the legs will rest on the bottom of the tub, at the rear bottom corner region. After use the legs are swung 100 about their pivots against the sides of the board and the board returned to its position in the depression 26, so that the washboard will be out of the way and also in order that the tub may receive the body portion of the sink, without interference by the washboard.

105 When the sink is disposed at one side of the tub, clothes which have been washed in the tub can be placed in the sink to drain.

110 Having thus described the invention and its construction and operation, it will be understood that changes may be made in carrying the invention into effect, without departing from the principle thereof.

115 What I claim is:

1. In combination, a washtub, a movable sink fitting said tub and forming a closure therefor, and means engaging said sink about which the sink may be swung on a pivot, laterally away from the tub.
2. In combination, a washtub, a movable sink fitting said tub and forming a closure therefor, means engaging said sink about which the sink may be swung, on a pivot,

laterally away from the tub, and additional means for supporting the sink in its laterally moved position.

3. In combination, a washtub, a vertically and laterally movable sink fitting into and forming a closure for said tub, means engaging the sink for lifting it vertically out of and above the tub, said means including a pivot member, so that the sink may be 10 swung laterally away from the tub.

4. In combination, a washtub, a vertically and laterally movable sink fitting into the tub, means for lifting the sink vertically out of and above the tub, a pivot about 15 which the sink may be swung laterally away from the tub, and means for supporting the sink in its laterally swung position.

5. In combination, a washtub, a vertically and laterally movable sink fitting into said 20 tub, a handle and lever arm pivotally connected to said tub, a vertically extending elbow arm and connections connecting said elbow arm to the lever arm and to the sink, so as to lift the sink vertically, said lifting 25 means including a pivot enabling the sink to be swung laterally away from the tub.

6. In combination, a washtub, a vertically and laterally movable sink fitting into said tub, said sink provided with a perforated 30 cornerpiece, and lifting means including a pivot member for lifting the sink vertically out of and above the tub, said pivot member passing through the perforated corner- 35 piece of the sink, so that the sink may be swung laterally away from the tub.

7. In combination, a washtub, a vertically and laterally movable sink fitting into said tub, said sink provided with a perforated cornerpiece, a handle and lever arm pivot- 40 ally connected to said tub, a vertically ex- tending elbow arm, a pin and slot connec- 45 tion between said lever arm and elbow arm, and a hook member carried by the elbow arm, passing through the perforated cor- 50 nerpiece of the sink, so that the sink may be lifted vertically out of and above the tub, said hook member serving as a pivot so as to enable the sink to be swung laterally away from the tub.

50 8. In combination, a washtub, a vertically and laterally movable sink fitting into said tub and forming a closure therefor, means for lifting said sink vertically out of and above the tub, and a drain pipe carried by 55 the sink, arranged in one corner thereof, said drain pipe serving as a pivot about which the sink may be swung laterally away from the tub.

9. In combination, a washtub, a vertically and laterally movable sink fitting into said tub and forming a closure therefore, means for lifting said sink vertically out of and above the tub, a drain conduit in a corner of the tub, and a drain pipe carried by the 65 sink telescoping with said drain conduit,

said pipe adapted to slide upward when the sink is lifted vertically and the telescopic construction affording a pivot about which the sink may be swung laterally away from the tub.

10. In combination, a washtub, a vertically and laterally movable sink fitting into said tub, means including a vertically re- 70 ciprocable elbow arm and a member connected to said arm for engaging the sink and lifting the sink vertically out of and above said tub, a drain conduit mounted in and projecting upward in said tub, a drain pipe carried by the sink telescoping with said drain conduit, said member and pipe serving 80 as pivot means about which the sink may be swung laterally away from the tub.

11. In combination, a washtub, a movable sink, forming a closure therefor, said sink adapted to be moved laterally away from the 85 tub to expose the tub, and a sink supporting member associated with said tub, upon which the sink rests and is supported in its laterally moved position.

12. In combination, a washtub, a laterally movable sink forming a closure therefor, means for swinging said sink laterally on a pivot, away from the tub to expose the tub, and a sink supporting member associated 95 with said tub, upon which the sink rests and is supported in its laterally swung position.

13. In combination, a washtub, a vertically and laterally movable sink fitting into said tub, means for lifting said sink vertically out of and above the tub, so that the sink may be swung on a pivot laterally away from the tub, and a hinged cover section associated with said tub, for normally enclosing and adapted to be swung to expose, 100 the sink lifting means, said cover section serving as a supporting member upon which the sink rests and is supported in its laterally swung position.

14. In combination, a washtub, a movable sink fitting into said tub, means for lifting the sink vertically out of and above the tub, pivot means about which the sink may be swung laterally away from the tub, and a hamper associated with said tub for supporting the sink in its laterally swung position.

15. In combination, a washtub, a movable sink fitting into said tub, means for lifting the sink vertically out of and above the tub, 120 pivot means about which the sink may be swung laterally away from the tub, and a hamper associated with said tub, said hamper having a hinged cover section, normally enclosing the sink lifting means, said cover 125 section adapted to support the sink in its laterally swung position.

16. In combination, a washtub, a laterally movable sink, fitting said tub, and a hamper associated with said tub, said ham- 130

per comprising a bottom compartment having walls enclosing the space beneath the tub, between the tub and the floor, and a vertical compartment having walls contiguous with and enclosing a space adjacent to the side of the tub, said vertical section serving to support the sink in its laterally moved position.

17. In combination, a washtub, a vertically and laterally movable sink, fitting into said tub, means for lifting said sink vertically, so that the sink may be moved laterally, a hamper associated with said tub, said hamper comprising a bottom compartment having walls enclosing the space beneath the tub, and a vertical compartment having walls contiguous with and enclosing a space adjacent the side of the tub, and a hinged cover section for said vertical compartment, said cover section normally enclosing the sink lifting means and adapted to swing horizontally to expose the same for operation, said cover section also serving to support the sink in its laterally moved position.

18. In combination, a washtub, a vertically and laterally movable sink fitting into said tub and forming a closure therefor, said sink provided with a perforated cornerpiece, a splashboard, a pair of faucets mounted in said splashboard, for supplying water to said sink and tub respectively, a drain for said tub, a drain conduit mounted in said tub, a sleeve drain pipe carried by the sink telescoping with said drain conduit, a hamper associated with said tub, said hamper provided with a hinged cover section, a handle and lever arm pivotally connected to said tub and normally enclosed by the cover section of said hamper, a vertically extending elbow arm connected to said lever arm and projecting through a cutout portion of the cover section of the hamper, a hook member carried by said elbow arm, passing through the perforated cornerpiece of the sink, and means for securing the hook member against vertical movement in the cornerpiece.

In testimony whereof I affix my signature.
LOUIS SCHÖEN.
